UNITED STATES PATENT OFFICE.

FRANK H. NICHOLSON, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed September 8, 1920. Serial No. 408,810.

To all whom it may concern:

Be it known that I, FRANK H. NICHOLSON, a citizen of the United States, residing at Wilkinsburg, in the county of Allegheny and State of Pennsylvania, have invented certain new and useful Improvements in Railway-Traffic-Controlling Apparatus, of which the following is a specification.

My invention relates to railway traffic controlling apparatus of the type comprising a railway vehicle, and governing means thereon including a speed responsive device operatively connected with a wheel of the vehicle. The proper operation of apparatus of this character depends, of course, on the integrity of the connection between the vehicle wheel and the speed responsive device; if this connection becomes broken the governing means will cease to function properly and a dangerous condition may arise.

One feature of my invention is the provision, in connection with apparatus of the character referred to, of means for detecting breakage of the connection between the vehicle wheel and the speed responsive device.

I will describe several forms of apparatus embodying my invention, and will then point out the novel features thereof in claims.

In the accompanying drawings, Fig. 1 is a view, partly diagrammatic, showing a railway vehicle equipped with one form of apparatus embodying my invention. Figs. 2 and 3 are views showing modifications of the apparatus shown in Fig. 1 and also embodying my invention.

Similar reference characters refer to similar parts in each of the views.

Referring first to Fig. 1, the reference character V designates a railway vehicle which is here represented by an axle 10 and a pair of wheels 11 and 11^a. Mounted on the vehicle V is a speed responsive device C which, as here shown, is a centrifugal device. This device is driven by a wheel of the vehicle, the operating connection comprising a beveled gear 12 fixed to the axle 10, a second beveled gear 13 meshing with the first, a shaft 14 connected with gear 13 and carrying a beveled gear 70, and a beveled gear 71 meshing with gear 70 and attached to the shaft 72 of the centrifugal device C .

The speed responsive device C is a part 55 of means for governing the vehicle V . This means may be of any desired type, and it is not shown in the drawing for the reason that it is not required for a complete disclosure of the present invention. The device C is preferably arranged to co-operate with the other elements of the governing means through the medium of a plate 15 which is operatively connected with the device C , and the horizontal position of which 60 is varied in accordance with the speed condition of the device C .

The speed responsive device C is so arranged that if any part of the driving connection between the axle 10 and the shaft 70 should break while the vehicle is in motion, the plate 15 will move from a given higher speed position to a given lower speed position in an interval of time which is considerably less than the time required for the vehicle to change from the corresponding higher speed to the corresponding lower speed at maximum rate of deceleration. For example, if some part of the driving connection should break while the vehicle is 75 traveling at 20 miles per hour or more, the plate 15 will move to the 5 mile per hour position in approximately one-half second, whereas, if a full service brake application is made while the vehicle is traveling at 20 80 miles per hour or more it will require approximately six seconds for the speed of the vehicle to be reduced from 20 miles per hour to five miles per hour.

I have taken advantage of this difference to indicate a failure of the driving connection between the speed responsive device C and the vehicle axle 10, and I accomplish this by the provision of slow-acting means which is set into operation when the plate 15 reaches the 20 85 mile per hour position while the centrifugal device C is closing, and which means will operate to apply the brakes if the plate 15 reaches the 5 mile per hour position in an interval of time materially less than six seconds. 90

The reference character R designates a timing reservoir which is constantly connected, by pipes 16 and 17, with the upper end of a cylinder 23 containing a piston 24. 95 The reservoir R is also connected by pipes 16 and 18 with a two-way valve A , which valve is operated in the manner hereinafter 100.

explained. Valve A is biased to the right hand position by a spring 21, and when in this position it connects the reservoir R with atmosphere through an exhaust port 22.

5 When, however, the valve A is reversed, that is, shifted to the left, it disconnects reservoir R from the exhaust port 22 and connects this reservoir with a pipe 19 which leads to a suitable source of fluid pressure, 10 such as the main reservoir of the braking system. The pipe 19 is provided with an orifice 20 of restricted area so that when the valve A is reversed, a considerable period of time, such, for example, as four seconds, is required to raise the pressure in reservoir R to the main reservoir pressure.

Opening into the cylinder 23 near the bottom thereof is a pipe 26 which leads to a valve B. This valve B is normally closed 20 by a spring 33, but may be opened by the plate 15, as hereinafter explained. When valve B is open it connects the pipe 26 with a pipe 27 leading to a brake application valve D.

25 The brake application valve D comprises a slide valve 28 which is attached to a piston 29 operating in a cylinder 30. Fluid pressure from a suitable source, such as the main reservoir, is supplied to the valve body 34 through a pipe 19^a, and the piston 29 is provided with a small port 32 to permit this pressure to pass to the left hand side of the piston. The piston 29 and the slide valve 28 are biased to their right hand positions, 30 wherein they are shown in the drawing, by means of a spring 31. When the parts of the valve device D occupy this position the brakes are released, but when the piston and slide valve move to the left an automatic application of the brakes occurs. The mechanism for causing the brake application is not illustrated because it is not essential to a disclosure of the present invention. In 40 accordance with usual practice the application would be effected by causing the slide valve 28 to open the brake pipe to atmosphere when shifted to its left hand position.

The lower end of cylinder 23 is provided 50 with an exhaust port 25, which port is closed, however, by an extension 24^a on the piston 24 when this piston is at the lower end of its cylinder. It follows that when the piston 24 rises, the pipe 26 is opened to atmosphere through the port 25.

55 The operation of the apparatus shown in Fig. 1 is as follows: As illustrated in this view, the plate 15 is in the position corresponding to a vehicle speed above 20 miles per hour. I will now assume that the speed 60 of the vehicle is reduced to zero. When the speed reaches 20 miles per hour, a stem 35 carried by plate 15 engages with the stem of valve A to shift this valve to the left in opposition to the action of spring 21. This reversal of valve A connects the reservoir R

with pipe 19 leading to the main reservoir, so that fluid pressure is gradually admitted to reservoir R. As the speed of the vehicle reduces, stem 35 is permitted to move to the right with respect to the plate 15 by the compression of spring 36, so that this stem does not interfere with the movement of the plate 15. When a speed of 5 miles per hour is reached, valve B is opened, due to the engagement of a stud 37 with the stem of this valve. This can not happen, however, until at least six seconds after the reversal of valve A, and since only 4 seconds are required to charge the reservoir R to main reservoir pressure, it follows, 70 that this pressure will be reached prior to the opening of valve B. The opening of valve B will admit main reservoir pressure from valve D and pipe 27 to the lower side of piston 24, but the upper surface of this piston is now exposed to main reservoir pressure, and inasmuch as the effective area of the upper surface is greater than the effective area of the under surface, it follows that piston 24 75 will remain in its lowest position, so that pipe 26 is not opened to atmosphere through port 25. The opening of valve B has no effect, therefore, on the brake application valve D, and, consequently, an automatic application of the brakes is not incurred. When the speed of the vehicle increases, the valve B will close at the five mile per hour point, and valve A will return to its normal 80 position when 20 miles per hour is reached, so that reservoir R will then be exhausted to atmosphere through port 22. The parts of the apparatus are thus restored to the 85 positions in which they are shown in the drawing.

I will now assume that while the vehicle is traveling at more than 20 miles per hour the connection between the centrifugal device C and the vehicle axle 10 becomes broken. The centrifugal device C will then close at a more rapid rate than before, that is, the plate 15 will move from the 20 mile per hour position to the 5 mile per hour position in about one-half of one second. At the 20 mile per hour position valve A 110 will be reversed and air at main reservoir pressure will start to flow through the restricted orifice 20 and into reservoir R; but when the 5 mile per hour position is reached it is obvious that the pressure in reservoir R will still be considerably less than main reservoir pressure. It follows that when valve B opens, the pressure on the lower surface of piston 24 will be considerably in 115 excess of the pressure on the upper surface of this piston, so that the piston will be raised. This movement of the piston 24 opens pipe 26 to atmosphere through port 25 so that the pressure on the left hand face of piston 29 in valve D is suddenly re- 120

duced. The main reservoir pressure on the right hand face of piston 29 then moves this piston together with slide valve 28 to the left, thereby causing an automatic application of the vehicle brakes. When the pressure in pipe 26 is reduced to a low value, piston 24 drops and closes exhaust port 25, but the brakes do not release because pipe 27 is then connected with atmosphere through pipe 38, chamber 39 in slide valve 28, pipe 40 and port 41 in a hand release valve E. This hand release valve comprises a plunger 42 which may be depressed by a push button 43 to stop the flow of fluid pressure from pipe 40 to atmosphere. When the hand release valve E is operated in this manner the brake application valve D will return to its normal position as soon as the pressure on the left hand surface of piston 29 reaches a certain value, whereupon the brakes will be released.

It will be seen from the foregoing that I have provided a slow-acting means which is set into operation when the vehicle speed is reduced to 20 miles per hour, and which will cause an automatic application of the brakes if the plate 15 reaches the 5 mile per hour position in less than a fixed interval of time. It is understood, however, that the two positions of plate 15 which I have specified are chosen arbitrarily, and that radical departures may be made therefrom without departing from the scope of my invention.

Referring now to Fig. 2, the apparatus shown in this view differs from that shown in Fig. 1 principally in the manner in which the brake application valve D is governed by the pressure in reservoir R. In Fig. 2 the valves A and B are, for convenience, mounted on opposite sides of the plate 15, and are actuated by a single stud 35 carried by this plate. The stud 35 is mounted to slide in its supporting plate and is biased to the right by a spring 36. At all speeds above 20 miles per hour the right hand end of this stud engages the stem of valve A and so holds this valve to the right, in which position the reservoir R is disconnected from the main reservoir pipe 19 and is connected with atmosphere through the exhaust orifice in the corrugated stem of the valve. When the speed of the vehicle is reduced to 20 miles per hour, however, the stud 35 leaves the stem of valve A and so permits this valve to be reversed by the fluid pressure in pipe 19, whereupon this pressure is admitted to reservoir R through the orifice 20 of restricted area and through pipe 44.

Leading from the left hand end of the timing reservoir R is a pipe 45 which is connected with a second pipe 46 through a ball check valve 47. This valve is so arranged as to permit fluid pressure to pass from pipe 46 into pipe 45, but to prevent the transfer

of fluid in the opposite direction. Pipe 46 is connected at times with pipe 27 through a valve B in the same manner as in Fig. 1, it being understood that pipe 27 leads to a brake application valve D as in Fig. 1. When the speed of the vehicle is reduced to 5 miles per hour, the left hand end of the stud 35 engages the stem of valve B and so opens this valve.

Assuming the same values for time and speed as were assumed in connection with Fig. 1, the operation of the apparatus shown in Fig. 2 is as follows:

With the apparatus in proper order, if the speed of the vehicle is reduced, when 20 miles per hour is reached, the charging of reservoir R begins, but the pressure in this reservoir reaches main reservoir pressure before the speed of the vehicle reaches 5 miles per hour. Consequently when the latter speed is reached and the valve B is opened, the pressures on the opposite sides of the ball check valve 47 are equal, so that there is no change of pressure in the pipe 27 which controls the brake valve application D; it follows, therefore, that the valve D is not affected.

Assuming now that the driving connection (Fig. 1) between the centrifugal device C and the vehicle axle becomes broken while the speed of the vehicle is above 20 miles per hour, it will be apparent that the pressure in reservoir R will not reach main reservoir pressure by the time valve B opens. Pressure from pipe 27 will, therefore, flow past the ball check valve 47 and into the timing reservoir R, and the consequent reduction in the pressure on the left hand face of piston 29 (Fig. 1) will cause an operation of the valve D to apply the brakes. The brakes may be released in the same manner as before, that is, by closing the hand release valve E and holding it closed until sufficient pressure is accumulated in the left hand end of cylinder 30 to restore the slide valve 28 to its initial position.

Referring now to Fig. 3, the apparatus here shown is in certain respects the electrical equivalent of the apparatus shown in Figs. 1 and 2. In Fig. 3 the reservoir R is connected with atmosphere or with the main reservoir by means of a valve A', which is controlled by an electromagnet 50. When the magnet 50 is de-energized, the reservoir R is opened to atmosphere through exhaust port 22, but when the magnet becomes energized the reservoir R is disconnected from atmosphere and is connected with the main reservoir through pipe 19. The left hand end of the timing reservoir R is connected with a pressure responsive device 52 which closes a contact 53 when the pressure in the reservoir R reaches the value of the main reservoir pressure.

The plate 15, which is moved by the speed

responsive device C of Fig. 1, is provided with a block 54 of insulating material which co-operates with two contacts 48 and 49 in such manner that contact 48 is closed when the plate 15 is in the 20 mile per hour position and remains closed at all speeds from 20 miles per hour to 0 miles per hour, inclusive, and that contact 49 is opened when the plate reaches the 5 mile per hour position. These two contacts control the electrical apparatus in the following manner: While contact 49 is closed, a brake application valve D^a is closed because of the closure of the following circuit: from battery F, through wire 59, contact 49, wires 60 and 66, magnet winding 55, and wires 61 and 62 to battery F. As long as the magnet winding 55 is energized, armature 56 is held in such position that valve D^a is closed. When this magnet winding becomes de-energized, however, the armature 56 together with the plunger 56^a will drop, due to gravity and to pressure in the brake pipe P, and so will open this pipe to atmosphere and will cause an application of the brakes. The armature and plunger are permitted to fall until the armature rests against a plate 57 which is at such a distance from the magnet winding 55 that the armature will not again be raised when this winding becomes energized. The plate 57 is, however, provided with a stem passing through a fixed block 58, the lower end of which stem carries a push button 57^a. This push button may be elevated by the engineer or driver of the vehicle to restore the plunger 56^a and so to release the brakes.

When the pressure controlled contact 53 is closed, the brake application valve D^a is held closed by an auxiliary circuit which passes from battery F, through wires 63 and 64, contact 53, wires 65 and 66, magnet winding 55, and wires 61 and 62 to the battery F.

The circuit for magnet 50 is from battery F, through wires 63 and 67, contact 48, wire 68, winding of magnet 50 and wires 69 and 62 to battery F.

The operation of the apparatus shown in Fig. 3 is as follows:

When the speed of the vehicle is above 5 miles per hour, contact 49 is closed, so that magnet 55 is energized and valve D^a is closed. Assuming that the speed of the vehicle is above 20 miles per hour and that the speed then decreases, it is apparent that when the 20 mile per hour point is reached magnet 50 will become energized and reservoir R will begin to charge. The charging will be completed and contact 53 will close before the speed of the vehicle can be reduced to 5 miles per hour. When the latter speed is reached, the normal circuit for brake valve D^a will be opened at contact 49, but the auxiliary circuit for this valve will in the meantime have been closed by

contact 53, so that the valve D^a will remain closed. That is, it is understood that the time required to charge reservoir R to main reservoir pressure is less than the time required for the vehicle to reduce from 20 miles per hour to 5 miles per hour at maximum rate of deceleration.

Assuming now that the driving connection for the centrifugal device C (Fig. 1) breaks while the speed of the vehicle is above 20 miles per hour, it is apparent that contact 49 will open before contact 53 closes, and that, consequently valve D^a will be released to cause an application of the brakes. The brakes can then be released by raising the plunger 57 after contact 53 has closed.

In connection with the apparatus shown in Fig. 3 it is apparent that when the vehicle is out of service and there is no pressure in the main reservoir, valve D^a will be open so that the braking system cannot be charged with fluid pressure without the provision of means for preventing the escape of this pressure at the valve D^a. This may, of course, be prevented by holding the valve D^a closed manually during the building up of pressure in the braking system, or it may be prevented by any other suitable means, which, however, forms no part of my present invention.

In connection with all three of the views it will be evident that after the vehicle speed has been held below 20 miles per hour for a certain period such for example as 5 seconds, a failure of the driving connection between the vehicle axle and the speed responsive device will not cause an application of the vehicle brakes. The failure of the driving apparatus at speeds below 20 miles per hour may, if desired, be indicated in any suitable manner such as by a pointer attached to the plate 15 and located where it can readily be seen by the engineer or driver of the vehicle.

Although I have herein shown and described only three forms of apparatus embodying my invention, it is understood that various changes and modifications may be made therein within the scope of the appended claims without departing from the spirit and scope of my invention.

Having thus described my invention, what I claim is:

1. In combination, a railway vehicle, a centrifugal device operatively connected with a wheel thereof and forming part of means for governing the vehicle, and separate means for governing the vehicle and effective only if said centrifugal device closes at a rate greater than the rate corresponding to maximum rate of deceleration of the vehicle.

2. In combination, a railway vehicle, a centrifugal device operatively connected with a wheel thereof and forming part of

means for governing the vehicle, and separate means for governing the vehicle if said centrifugal device closes at a predetermined rate.

5 3. In combination, a railway vehicle, a speed responsive device operatively connected with a wheel thereof and forming part of means for governing the vehicle, and separate means for governing the vehicle 10 responsive to a change of said device from a higher speed condition to a lower speed condition in a given interval of time.

4. In combination, a railway vehicle, a speed responsive device operatively connected with a wheel thereof and forming part of means for governing the vehicle, and other means for governing the vehicle if said device changes from one speed condition to another speed condition in a given 20 interval of time or less.

5. In combination, a railway vehicle, a speed responsive device operatively connected with a wheel thereof and forming part of means for governing the vehicle, and other means for governing the vehicle if said device changes from a given higher speed condition to a given lower speed condition in a given interval of time or less.

6. In combination, a railway vehicle, a speed responsive device operatively connected with a wheel thereof and forming part of means for governing the vehicle, and safety means controlled by said device and set into operation if the device changes 35 from one speed condition to another speed condition in a given interval of time or less.

7. In combination, a railway vehicle, a speed responsive device operatively connected with a wheel thereof and forming 40 part of means for governing the vehicle, and separate means of governing the vehicle controlled by said device and set into operation only if the device changes from a higher speed condition to a lower speed condition 45 in a shorter interval of time than that required for the vehicle to change from the corresponding higher speed to the corresponding lower speed at a maximum rate of deceleration.

50 8. Railway traffic controlling apparatus comprising a vehicle, and governing means thereon including a speed responsive device connected with a wheel of the vehicle, characterized by the combination therewith of a timing reservoir, means controlled by said device for connecting said reservoir with a source of fluid pressure through a restricted orifice when said device reaches a given speed condition while changing from higher 55 to lower speed, and safety means set into operation if said device reaches a given lower speed condition before the pressure in said reservoir reaches a given value.

9. Railway traffic controlling apparatus 60 comprising a vehicle, and governing means

thereon including a speed responsive device connected with a wheel of the vehicle, characterized by the combination therewith of slow-acting means set into operation at a given speed while said device is changing from a higher to a lower speed condition, and safety means rendered effective if said speed responsive device reaches a lower given speed condition before the operation of said slow-acting means is completed.

10. Railway traffic controlling apparatus comprising a vehicle, and governing means thereon including a speed responsive device which is connected with a wheel of the vehicle and which, if disconnected from the wheel while the vehicle is in motion, will change from a given higher speed condition to a given lower speed condition in a considerably shorter interval of time than the time required for the vehicle to change from

the corresponding higher to the corresponding lower speed at maximum rate of deceleration; characterized by the combination therewith of slow-acting means set into operation when said device passes through said given higher speed condition while changing from higher to lower speed, the time interval of said slow-acting means

being less than the minimum time required for the vehicle to decelerate from such higher to such lower speed but greater than the time taken by said speed responsive to change from said higher to said lower speed condition when disconnected from the vehicle wheel, and safety means rendered effective if the speed responsive device reaches such lower speed condition before the operation of said slow-acting means is completed.

11. Railway traffic controlling apparatus comprising a vehicle, and governing means thereon including a speed responsive device which is connected with a wheel of the vehicle and which, if disconnected from the wheel while the vehicle is in motion, will change from a given higher speed condition to a given lower speed condition in a time interval A which is considerably less than the time interval B required for the vehicle

to change from the corresponding higher speed to the corresponding lower speed at maximum rate of deceleration, characterized by the combination therewith of slow-acting means set into operation when said device passes through said higher speed condition while changing from higher to lower speed, the time interval of said slow-acting means

being less than B and greater than A, and safety means rendered effective if the speed responsive device reaches such lower speed condition before the operation of said slow-acting means is completed.

12. In combination, a railway vehicle, a speed responsive device thereon forming part of mechanism for governing the vehicle,

means for driving said device at a speed proportional to the speed of the vehicle, and safety apparatus controlled by the rate at which said device changes from a condition corresponding to one speed to a condition corresponding to another speed.

13. In combination, a railway vehicle, a speed responsive device thereon, means for driving said device at a speed proportional to the speed of the vehicle, and safety apparatus controlled by the rate at which said device changes from one speed condition to another.

14. In combination, a railway vehicle, a centrifugal device thereon, means for driving said device at a speed proportional to

the speed of the vehicle, and safety apparatus controlled by the rate at which said device closes.

15. In combination, a railway vehicle, a speed responsive device thereon, means for driving said device at a speed proportional to the speed of the vehicle, and means responsive to the rate of change of said device from one speed condition to another for applying the brakes of the vehicle.

In testimony whereof I affix my signature in presence of two witnesses.

FRANK H. NICHOLSON.
